UNITED STATES PATENT OFFICE.

ISAIAH D. BUCK, OF PHILADELPHIA, PENNSYLVANIA.

CLOTHES-WASHER.

No. 867,873.

Specification of Letters Patent.

Patented Oct. 8, 1907.

Application filed October 3, 1906. Serial No. 337,206.

To all whom it may concern:

Be it known that I, ISAIAH D. BUCK, a citizen of the United States, residing in Philadelphia, Pennsylvania, have invented certain Improvements in Clothes-Washers, of which the following is a specification.

My invention relates to certain improvements in washing machines for which a patent was granted to me on the 24th day of November, 1874, No. 157,062.

The object of my present invention is to improve the construction of the washing machine making it easy to operate and so that it will more thoroughly clean the clothes.

In the accompanying drawings, Figure 1, is a perspective view of my improved washing machine; Fig. 2, is an inverted plan view; Fig. 3, is a transverse sectional view on the line 3—3, Fig. 2, and Fig. 4, is a longitudinal sectional view on the line 4—4, Fig. 2.

My improved washing machine is of the type that can be used in an ordinary wash tub or a stationary tub, a special tub is not necessary.

A is the body of the machine having two series of perforations a, a' as shown in Fig. 2, one series on one side of the center and the other series on the opposite side.

B is a cover board secured in any suitable manner to the body A; c, c' are transverse passages extending from the center towards each edge, and connect with the perforations of each row.

D' are valves arranged to close the openings c, c' respectively, in the present instance the body portion 30 is notched at a^2 and the cover B is cut short to form a recess at each side for the reception of the valves, so that the valves are protected. Each valve in the present instance consists of a strip of rubber secured by a row of nails to the cover B, and so arranged that they 35 will close with suction and open when a body of water is forced through the perforations and passages.

Secured to the underside of the body portion is a series of transverse ribs E, each rib is V-shaped forming a pivot point e at the center on which the machine can 40 rock. On each end of the machine are plates F, F which are tapered and extend upwards a sufficient distance to form arms to which the handle member G is

attached, this handle is of such height that the machine can be rocked with very little exertion.

To operate the machine the clothes are placed in the 45 tub, either of the stationary or portable type, with sufficient water and soap, the machine is then placed upon the clothes and a rocking to and fro motion imparted to it, causing the machine to rock on the pivot e , the water is thus churned. When the machine is tilted towards 50 one side the water is forced through the clothes on that side escaping through the passages and valve, the clothes on the other side of the center are lifted due to the suction so that the water can gain access to the space between the clothes, and as the rocking movement proceeds, the clothes are thoroughly washed without rubbing or other destructive action. 55

I claim:—

1. The combination in a washing machine, of a body portion having a series of perforations and transverse 60 passages connecting certain of said perforations, a valve at each side of the machine, transverse ribs extending between each series of perforations and means for rocking the machine on said ribs, substantially as described.

2. The combination in a washing machine, of a body 65 portion having two series of perforations, and passages communicating with the perforations on one side of the center and the other set of passages communicating with the perforations on the other side of the center, valves 70 at each side of the machine arranged to close the outlets of the passages, with a series of transverse ribs on the under side of the body portion, constructed to serve as rockers for the machine and projecting beyond the surface of the body portion in which the perforations are 75 formed, substantially as described.

3. The combination in a washing machine, of a perforated body portion having transverse passages therein, and a cover plate, said body portion being notched at each side, a flat rubber valve secured in each notched portion 80 of the body and arranged to close the transverse passages, side plates and a handle, and transverse ribs extending downwards from the body portion, said ribs being deeper at the center than at the sides, substantially as described.

In testimony whereof, I have signed my name to this 85 specification, in the presence of two subscribing witnesses.

ISAIAH D. BUCK.
